CLAIM

The ornamental design for a baby bottle medicant device, as shown.

DESCRIPTION

FIG. 1 is a front elevation of a baby bottle medicant device showing my new design;

FIG. 2 is a top plan view thereof;

FIG. 3 is a bottom plan view thereof; and

FIG. 4 is a cross-section taken on line 4—4 of FIG. 2.

*Fig.2.**Fig.1.**Fig.4.**Fig.3.*
